DAMPING DEVICE FOR INFLATABLE FLOATS
Herbert J. Fritzsche, Dover, N.J., assignor, by mesne assignments, to the United States of America as represented by the Secretary of the Navy
Filed Mar. 14, 1966, Ser. No. 535,656
1 Claim. (Cl. 114—121)

ABSTRACT OF THE DISCLOSURE

A stabilized floating device comprising an inflatable bag having a plurality of spaced rows of inflatable tabs of flexible material. The plurality of tabs are staggered in adjacent rows and each tab is provided with a hole that provides an increased effective peripheral length.

The present invention relates to damping devices and more particularly to damping devices for inflatable floats that are used for providing additional buoyancy to structures, such as aircraft.

Various types of damping devices are known for attaching to floating objects to limit the amount of motion due to waves and wind. Generally, these damping devices are comprised of vertical or horizontal plates that are attached to a device and serve as fins. The present invention relates to improved damping devices for a flotation bag that are made internal with the bag and the damping devices deflate with the bag for stowage.

The damping device of the present invention consists of a plurality of rows of tabs that are integral with a flotation bag that is to be damped. Tabs in alternate rows are staggered and all the tabs are inflated with the bag which eliminates the complexity of a separate inflation system. The damping device is simple, compact, lightweight, and provides effective damping to a flotation bag.

It is therefore a general object of the present invention to provide improved damping means for a flotation bag.

Other objects and advantages of the present invention will be readily appreciated as the same becomes better understood by reference to the following detailed description when considered in connection with the accompanying drawing wherein:

FIGURE 1 is a partial side view showing a plurality of rows of tabs on a flotation bag;

FIGURE 2 is a bottom view of the devices shown in FIGURE 1;

FIGURE 3 is a partial perspective view showing a single tab attached to a portion of a flotation bag;

FIGURE 4 is a sectional view taken on line 4—4 of FIGURE 3; and

FIGURE 5 is a partial perspective view of a different embodiment of a tab.

Referring now to the drawing, there is shown a flotation bag 11 which, by way of example, might be cylindrical in design and have hemispherical ends thereon.

2

Flotation bag 11 might be constructed of Nylon or Dacron fabric combined with a suitable elastomer so that the bag is both water-tight and air-tight. A plurality of rows of tabs 12 are attached integral to flotation bag 11 so that the tabs 12 are inflated upon inflation of bag 11. By way of example, five rows of tabs 12 are shown provided on bag 11, however, either a smaller or larger number of rows might be provided without departing from the scope of the invention. Also, by way of example, six tabs are shown in each row. Tabs 12 in adjacent rows are staggered, or alternately spaced, so that a line passing the center of a particular tab will bisect the spacing between adjacent tabs in an adjacent row. This alternate spacing of tabs and also the spacing between rows of tabs tends to minimize flow interference effects.

As best shown in FIGURE 4 of the drawings, an orifice or opening 13 is provided in bag 11 for each tab 12 and thus tabs 12 are inflated upon inflation of bag 11. In FIGURE 5 of the drawing there is shown a tab 12 that is provided with a hole 14. It has been determined that the drag coefficient is a function of P^2/A ratio, where P is the total periphery of the tabs and A is the area. Thus the addition of hole 14 in tab 12 is an effective means of further increasing the ratio of P^2/A .

It can thus be seen that the present invention provides an improved damping device for a bag that is to be attached to a floating object. The multi-tab configuration is simple, compact, and lightweight, and its relative value of P^2/A makes it an effective damper. The tabs are inflatable with the bag and thus there is eliminated the complexity of a separate inflation system.

Obviously many modifications and variations of the present invention are possible in the light of the above teachings. It is to be understood, that within the scope of the appended claim, the invention may be practiced otherwise than as specifically described.

What is claimed is:

A device for providing stabilized support for a floating structure comprising:

an elongated inflatable bag of flexible material, a plurality of spaced rows of inflatable tabs of flexible material attached to the outer periphery of said inflatable bag, each said tab being provided with a through hole whereby the effective peripheral length of each said tab is increased, and wherein said tabs in adjacent rows are staggered; and

a plurality of openings connecting the inside of said inflatable tabs to the inside of said tabs whereby said tabs are inflated upon inflation of said bag.
